UNITED STATES PATENT OFFICE.

JULIUS A. BIDWELL, OF IVANPAH, CALIFORNIA.

AMALGAMATING-PAN.

SPECIFICATION forming part of Letters Patent No. 313,164, dated March 3, 1885.

Application filed November 28, 1884. (No model.)

To all whom it may concern:

Be it known that I, JULIUS A. BIDWELL, of Ivanpah, county of San Bernardino, State of California, have invented an Improvement 5 in Amalgamating-Pans; and I do hereby declare the following to be a full, clear, and exact description of the same.

My invention relates to certain improvements in amalgamating-pans in which a mass 10 of quicksilver pulp and chemicals is heated by steam; and it consists of an attachment or device within which a thermometer is contained and through which the temperature may be communicated directly to the thermometer-bulb, while the stem and index-plate 15 project to the exterior of the pan, so that they may be readily inspected.

Referring to the accompanying drawings for a more complete explanation of my invention, 20 Figure 1 is a side elevation of a pan with a part broken away, showing my device applied so as to project from the side of the pan. Fig. 2 is an enlarged view of this form of the device. Fig. 3 shows the pan with the device 25 applied so as to project vertically through the top. Fig. 4 is an enlarged view of this form.

In a former patent, issued to me August 19, 1884, No. 303,693, I have shown an amalgamating-pan having an inverted siphon-shaped 30 receptacle or pipe filled with quicksilver, one end of the pipe extending into the pan, while the other projects outside and has a thermometer inserted into its outer end. I have found this device objectionable, because the quicksilver within the pipe soon becomes charged 35 with amalgam and solidifies, and the thermometer-bulb, being set at the outer end and exterior to the pan, does not show correctly the temperature. In my present invention A 40 is a hollow bulb, having a stem, B, extending outwardly from it, to which a pipe or extension, C, may be connected by a coupling, D.

Within the enlargement A the bulb E of a thermometer is placed. The stem F extends 45 outward and upward into the tube C. The upper portion of the tube C may have the side cut away, as shown at G, and an index or scale, H, may be placed behind it to show the point at which the mercury within the thermometer stands. This device may be inserted 50 into the amalgamating-pan I in any suitable

or desirable way. This style of pans is usually made of wood and closed, having stirring or agitating arms or mullers, which are caused to rotate within the pan by means of 55 a vertical shaft in the usual manner. When it is desired to apply this device to the side of the pan, an opening is made therein horizontally, and of sufficient diameter to receive the stem B, which is driven through it from the 60 inside, the bulb A thus remaining close to the side of the pan.

In order to hold the bulb squarely while the elbow or coupling D is being screwed upon its outer end, it may be flattened upon two opposite sides, so that a wrench may be applied to it, or it may have wedge-shaped lugs J, which can be driven into the side of the pan, so as to prevent the device from turning round. They serve also to hold it firmly in place after it 70 has been fixed. In this case the elbow D changes the direction from a horizontal to a vertical one, and the thermometer-tube must be bent so as to correspond with the curved elbow D. When the tube is in the same line 75 with the tube B, the thermometer may be straight, and the device may be inserted through a cover of the pan so that the enlargement A is within the contents from which it is heated.

In order to provide a good conductor, the chamber A is filled with mercury to such a point that it will stand slightly above the thermometer-bulb, and will thus convey the heat from the interior of the pan directly to the 85 thermometer-bulb. By this construction I am enabled to preserve the quicksilver in its fluid condition, as it has no direct communication with the contents of the pan, and by extending the bulb of the thermometer to its 90 interior end the heat of the contents of the pan will always be exactly indicated upon the scale outside.

Having thus described my invention, what I claim as new, and desire to secure by Letters 95 Patent, is—

1. The combination of an amalgamating-pan with a hollow chamber within which quicksilver is contained, a pipe or tube connected therewith and extending to the exterior of the pan, and a thermometer fixed so that its bulb is contained within the receiver while the stem 100

extends to the outside of the pan, substantially as herein described.

2. A closed hollow chamber containing quicksilver, fixed within an amalgamating-
5 pan, and having a tube extending outwardly from it, in combination with a thermometer the bulb of which lies within the quicksilver in the chamber while its stem lies within the

tube and has a scale placed exterior to the pan, substantially as herein described.

In witness whereof I have hereunto set my hand.

JULIUS A. BIDWELL.
